COLLAPSIBLE SPRINKLING CONTAINER

John C. Setecka, 1931 S. Austin Ave., Cicero, Ill.

Filed Apr. 9, 1962, Ser. No. 69,626

Term of patent 7 years

(Cl. D58—17)

FIG. 1 is a front elevational view of a collapsible sprinkling container, embodying my new design; and FIG. 2 is a top plan view thereof.

I claim:

The ornamental design for a collapsible sprinkling container, as shown and described.
